UNITED STATES PATENT OFFICE.

DANIEL L. IRVIN, OF CURWENSVILLE, PENNSYLVANIA, ASSIGNOR TO A. H. IRVIN COMPANY, INC., OF CURWENSVILLE, PENNSYLVANIA, A CORPORATION.

STAPLE BINDER.

Application filed October 20, 1921. Serial No. 509,067.

To all whom it may concern:

Be it known that I, DANIEL L. IRVIN, a citizen of the United States, residing at Curwensville, in the county of Clearfield and 5 State of Pennsylvania, have invented certain new and useful Improvements in Staple Binders, of which the following is a specification.

My invention relates to improvements in 10 staple binders, of the form shown in the application filed May 9, 1921, Serial No. 467, 936, by Berthold Jahn and Ernest Emil Kahl, and the patents issued under date of 15 August 9, 1921, to said Jahn and Kahl, Nos. 1,387,268 and 1,387,269, and the object of my improvement is to incorporate in a structure of the general form mentioned means for 20 cooperating with the individual staple that is in the path of the plunger and is the next to be severed from the staple strip and driven by the operation of the plunger, whereby 25 said individual staple will be positioned and directed for properly cooperating with the plunger and the anvil in effecting the binding of materials that are operated upon in the use of the binder in the usual and ordinary manner.

In the accompanying drawing:

Figure 1 is a side elevation of my improved staple binder.

Figure 2 is a plan view of the same, the handle being broken away.

Figure 3 is a front elevation of the same.

Figure 4 is a sectional view on the line 35 4-4 of Fig. 6, being on an enlarged scale.

Figure 5 is a side elevation of part of one of the side frames, as viewed from the inside.

Figure 6 is a plan view of the front end 40 portion of the filler piece, showing the die, the adjacent parts being shown in broken lines.

Figure 7 is a fragmentary front elevation, in part broken away, showing the parts 45 in a different position from that shown in Fig. 3.

Figure 8 is a perspective view of part of a staple strip.

Figure 9 is a side elevation in part broken 50 away.

The staple binder to which my invention is applied may correspond in the general form to any of those shown and described in any of the patents or the application men-

tioned or to other devices that operate on a 55 staple strip of similar form to the strip shown in Fig. 8, so that a brief description of such general structure will suffice in the present instance.

Such a general structure comprises a base 60 10 having at the front end the anvil 11 for clenching the staples 12 in cooperation with the plunger 13 after they have been severed from the staple strip and forced downwardly by the continued movement of the plunger, said staple strip being composed of a series of individual staples 12 that are connected in series.

At the rear end of the base 10 is a pair of 70 upstanding ears 14, positioned in spaced relation, that support the pivotal pin 15.

The base 10 serves as the fixed member, and a moving member, designated generally by the character 16, is operatively connected thereto by the pivotal pin 15.

A pair of ways 17 at the front part of the moving member 16, positioned in spaced relation, engage with the side edge portions of the plunger 13 and serve to guide the plunger in its upward and downward movement.

The filler piece 18 that extends along the bottom of the moving member 16, and is opposed to the base 10, is positioned between the two side plates 19 of the frame or casing; has the upper portion 20 reduced in 85 width so as to serve as the guide for the staple strip; supports by its front end the die 21; supports by the lower portion 22 suitable dowel pins 23 for positioning the side plates 19; and has the rear end portion extended between the ears 14 and pivotally supported by the pin 15.

The said bottom portion also has holes for the two holding screws for holding the side plates 19 in place, comprising the screw 95 24 at the rear and the screw 25 at the front.

The front screw serves also as the means for holding the die 21 in place, said die 21 being in the form of a removable piece.

The upper part of the casing for the moving member 16 is formed by the side plates 19 which have their body portions positioned in spaced relation to provide a housing for the staple moving or feeding mechanism that cooperates with the plunger 13. The form of the said upper part of the casing is generally triangular, with a sloping or inclined rear and upper wall 26, and the closure for 100 105

the said rear and upper portion is provided by means of inwardly turned, opposed flanges 27 on the side plates 19.

At the upper, front part of the casing,

6 being at the upper ends of the ways 17, is a seat 28 for a spring 29 that cooperates with a knob 30 at the upper end of the plunger 13 so as to tend to hold the said plunger in the uppermost position.

10 The staple strip feeding mechanism is similar to that shown and described in each of the specifications referred to above, being actuated by a lug 31 on the plunger 13, and comprising a feeding pawl 32 and a holding pawl 33.

The feeding pawl 32 is supported by a pivotally supported dog 34, the latter having a lug 35 cooperating with the lug 31 on the plunger 13, and a spring 36 serves

20 to position the said feed pawl 32 relatively to the dog 34.

A spring 37 serves to position the holding pawl 33.

The individual staples 12 are of U-shape, 25 as is usual, and they are connected together by means of connecting necks 38 that serve to inter-connect the yoke portions 39 of the adjacent individual staples 12, whereby there is provided a backbone 40 that extends continuously from end to end of the staple strip, said strip as a whole being designated by the character 41.

The yoke portions 39 extend transversely across the backbone 40 and in use the combined structure formed by said yoke portions 39 and backbone 40 rests upon the upper face of the reduced, upper portion 20 of the filler piece 18.

40 The legs 42 of the staples 12 hang downwardly from the ends of the yoke portions 39 and travel in the spaces 43 at the sides of said reduced, upper portion 20 and which spaces 43 are closed on the outer sides by the side plates 19.

45 Thus said reduced, upper portion 20 of the filler piece serves as the guide or support for the staple strip 41 and is the part that has the cutting edge at the front end for cooperating with the cutting edge on the plunger 13. The cutting edge 44 on the support 20 may be integral with the filler piece 18 or may be provided on a removable and adjustable die 21, as shown.

50 The cutting edge 45 on the plunger 13 operates to sever the neck 38 as the plunger is lowered and the continued movement of the plunger 13 serves to drive the severed staple 12 along the channel 46 between the filler piece 18 and the opposed front wall portions 47 of the ways 17. Previous to being severed the end staple 12 is held overhanging the filler piece 18, at the upper portion of the channel 46, and with the legs 42 held against the front wall portions 47, the projecting end portion of the neck 38 that

was left by the previous cut being housed within the space 48 between the opposed edges of said front wall portions 47 of the ways 17.

Thus it will be noted that the front wall 70 portions 47 are adapted to serve as guide ways for the front edge portions of the legs 42 as well as guide ways for the plunger 13.

I find it desirable to provide positive guide means for cooperating with the rear edge 75 faces of the said legs 42 of the staples 12, and I do this in the following manner:—Positioned generally in the vertical plane in alignment with the spaces 49 between the legs 42 of the end staple 12 and the next, 80 adjacent staple 12 are two pivotally supported guide members 50, one on each side, and supported by the side plates 19, and operating through suitable slots therein.

Said members 50 are made of sheet metal, 85 are actuated by the plunger 13, and have at the lower ends each a guide nose portion 51 that extends through a slot 52 in the side plate 19 and is adapted to be entered in the space 49 between the legs 42. At their upper ends in each case is a tripping nose 53 extended through a slot 54 that cooperates with the fin plate 55 that is mounted on the body 56 of the plunger 13 and that is extended inwardly to provide the tripping lug 31, already mentioned.

Just below the tripping nose 53 is a hinge lug 57 that is mounted on the pivotal pin 58. The body portion 59 extends along the outer face of the side plate 19, being disposed edgewise thereto and between the hinge lug 57 and the guide nose 51 is a recess 60 that is cut into the edge in which is housed a positioning spring 61, said spring tending to hold the guide nose 51 out of the guiding position between the legs 42. 100

105 The position mentioned is the normal position for said guide nose 51, so that under normal conditions the staple strip may be moved freely along the filler piece 18 so far as concerns the effect of the auxiliary guide members 50, as the fin plate 55 is normally above the tripping nose 53.

110 As the plunger descends the fin plate 55 enters between the two tripping noses 53 and forces these outwardly, thus bringing the guide noses 51 into the operating positions between adjacent legs 42 so that the staple 12 that is driven is guided at the rear as well as at the front.

115 When upon the return movement the plunger 13 is lifted by the spring 29 the springs 61 serve to remove the guide noses 51 from the engaging positions.

120 I claim as my invention:—

1. A staple binder comprising a casing having slots in the sidewalls thereof, a supporting bar mounted in said casing for supporting a staple strip that is composed of individual staples connected in series, said 125

bar having a cutting edge at one end, means for feeding said strip along said bar so that said strip will project beyond said cutting edge, means to limit such projection 5 of the strip to correspond to a single staple and operative also to serve as a guide for one edge portion of said single staple, a plunger having a cutting edge to cooperate with the cutting edge of the bar and operative to be driven so as to sever said single staple and drive the same, auxiliary guide means operating as levers extending through the slots in the casing for guiding the opposite edge portion of said single staple, 10 and means operated by the plunger for setting said auxiliary guide to guiding position.

2. A staple binder having a supporting bar for supporting a staple strip that is composed of individual staples connected in se- 20

ries, said bar having a cutting edge at one end, means for feeding said strip along said bar so that said strip will project beyond said cutting edge, means to limit such projection of the strip to correspond to a single 25 staple and operative also to serve as a guide for one edge portion of said single staple, a plunger having a cutting edge to cooperate with the cutting edge of the bar and operative to be driven so as to sever said 30 single staple and drive the same, auxiliary guide means comprising a pair of levers for guiding the opposite edge portion of the said single staple, each of said levers having a guide nose cooperating with the staple and a tripping nose, and means on the plunger cooperating with the tripping noses for setting the auxiliary guide means to guiding 35 position.

DANIEL L. IRVIN.
